UNITED STATES PATENT OFFICE.

EDWARD W. SHANNON, OF WATERBURY, CONNECTICUT, ASSIGNOR TO
THE ROGERS & HAMILTON COMPANY, OF SAME PLACE.

DIE FOR SWAGING SPOON AND FORK BLANKS.

SPECIFICATION forming part of Letters Patent No. 349,609, dated September 21, 1886.

Application filed July 3, 1886. Serial No. 207,073. (No model.)

To all whom it may concern:

Be it known that I, EDWARD W. SHANNON, a citizen of the United States, residing at Waterbury, in the county of New Haven and State 5 of Connecticut, have invented certain new and useful Improvements in Dies for Swaging Spoon and Fork Blanks; and I do hereby declare the following to be a full, clear, and exact description of the invention, such as will 10 enable others skilled in the art to which it appertains to make and use the same.

My invention relates to certain new and useful improvements in dies, such as are used for swaging up fork and spoon blanks, but is more 15 especially intended as an improvement upon Letters Patent of the United States No. 232,320, granted to William W. White the 14th day of September, 1880.

The object of the invention is to provide 20 dies whose operating-surfaces are so conformed as to apply the necessary lateral pressure to the blank for the thickening of the same vertically, but which will prevent any lengthening of said blank during the operation; and 25 with these ends in view my improvement consists in forming on the edges of the dies the corrugations hereinafter described for securing an exceedingly firm grip upon the material worked between them.

In order that such as are skilled in the art 30 to which my invention appertains may fully understand my improvement, I will describe the same in detail, referring by letter to the accompanying drawings, forming a part of this specification, and in which—

Figure 1 is an elevation of a set of dies and blocks, the spoon-blank being shown in section; Fig. 2, a similar view, but with the dies closed upon the blank; Fig. 3, a perspective of 40 the dies in proper position relative to a spoon-blank; Fig. 4, a perspective of a spoon-blank after the action of the dies; Fig. 5, a detail perspective of one of the dies provided with corrugations in place of the notches, and Fig. 45 6 a plan view of a blank formed between smooth-surfaced dies and intended for comparison with Fig. 4.

Similar letters denote like parts in all the figures of the drawings.

50 A are the dies, whose operating edges are

conformed to the shape of the central portion of a spoon-blank, as seen at Fig. 3. These dies may be operated by any convenient means whereby power may be applied to them.

B is a stationary block, upon which the dies 55 rest, and C is a movable block arranged above the block B and the dies, as shown at Figs. 1 and 2. The blocks B C hold the spoon-blank flat during the action of the dies, and the upper block is arranged to be raised slightly by 60 the metal as the latter is compressed, as shown at Fig. 2.

D are notches or corrugations formed in or upon the operating faces of the dies, and at right angles to the length thereof. 65

E is the spoon-blank.

My improved dies are operated after the manner described in the Letters Patent No. 232,320, hereinbefore referred to, and their function—viz., to compress the blank transversely to its length, and thereby both harden and thicken the metal thereof—is similar to the function performed by the means embraced in said Letters Patent, but with the important difference now to be set forth. The notched 70 or corrugated operating-surfaces, when forced against the blank, lay hold thereon, so that longitudinal stretching or spreading thereof is entirely obviated. As will be readily understood, this is caused by the upset of the metal 75 of the blank into the corrugations of the dies. Since the metal cannot expand longitudinally, the compression results in an increase of thickness only, instead of an increase both in length and thickness. 85

The tendency of the metal blank to elongate under transverse pressure is very great, and varies, of course, with every slight variation in the thickness of the metal. The advantage of my improvement will therefore be readily 90 recognized, since as no lengthening can occur, the finished blanks, while they may vary slightly in thickness, do not vary perceptibly in length.

I do not wish to be understood as laying 95 claim, broadly, in any sense to swaging-dies for operating upon spoon and fork blanks, nor do I desire to be understood as claiming as of my invention the arrangement of dies and blocks shown in the Letters Patent No. 232,320, 100

above referred to, but only my particular construction of dies as appears from this specification and drawings.

I claim and desire to secure by Letters Patent—

1. A pair of dies of the character described, having their operating-surfaces corrugated or roughened transversely to the length thereof, substantially as set forth.
2. A pair of dies as described, having formed

in their operating-surfaces a series of notches extending across said surfaces and substantially transverse to their length, as and for the purpose shown and described.

In testimony whereof I affix my signature 15
in presence of two witnesses.

EDWARD W. SHANNON.
